CLAIM

The ornamental design for an electronic tablet device case as shown and described.

DESCRIPTION

FIG. 1 is a perspective view of an electronic tablet device case taken from the top, right, and front;

FIG. 2 is another perspective view of the electronic tablet device case taken from the bottom, right, and back;

FIG. 3 is a front elevation view of the electronic tablet device case of FIG. 1;

FIG. 4 is a back elevation view of the electronic tablet device case of FIG. 1;

FIG. 5 is a right elevation view of the electronic tablet device case of FIG. 1;

FIG. 6 is a left elevation view of the electronic tablet device case of FIG. 1;

FIG. 7 is a top plan view of the electronic tablet device case of FIG. 1; and,

FIG. 8 is a bottom plan view of the electronic tablet device case of FIG. 1.

The broken lines in the drawings illustrate portions of the electronic tablet device case that form no part of the claimed design.
